UNITED STATES PATENT OFFICE.

CHARLES ADAMS GOODYEAR, OF TOMAH, WISCONSIN.

APPARATUS FOR HANDLING AND LOADING LUMBER.

SPECIFICATION forming part of Letters Patent No. 462,312, dated November 3, 1891.

Application filed March 15, 1890. Serial No. 344,021. (No model.)

To all whom it may concern:

Be it known that I, CHARLES ADAMS GOOD-
YEAR, of Tomah, in the county of Monroe and
State of Wisconsin, have invented certain new
5 and useful Improvements in Apparatus for
Handling and Loading Lumber, &c.; and I do
hereby declare that the following is a full,
clear, and exact description of the invention,
which will enable others skilled in the art to
10 which it pertains to make and use the same,
reference being had to the accompanying
drawings, and to the letters of reference
marked thereon, which form a part of this
specification.

15 The main object of my invention is to fa-
cilitate the handling and loading of lumber
and like materials.

It consists, essentially, of cross-supports
20 upon which the lumber, &c., is placed in proper
form for a load in an elevated position, so as
to permit of the vehicle to be loaded being
drawn under the same, upright levers ful-
crumed near their upper ends to an elevated
25 frame and adapted to hold said supports upon
their upper ends, and connections with the
lower ends of said lever by which said sup-
ports are lowered and the load resting thereon
is transferred to the vehicle, and of certain pec-
uliarities of construction and arrangement,
30 hereinafter particularly described, and point-
ed out in the claims.

In the accompanying drawings like letters
designate the same parts in the several fig-
ures.

35 Figure 1 is a perspective view of my im-
proved apparatus, and Fig. 2 is a vertical lon-
gitudinal section of the same on an enlarged
scale.

40 A A represents a rigid frame open at one
end to receive a wagon or other vehicle to be
loaded and having its sides of approximately
the height of the vehicle. To the upper side
beams of this frame are pivoted or hinged
45 levers B B, two or more on each side. These
levers on each side of the frame are connected
at or near their lower ends by bars C C. At
the end of the frame opposite the opening
for the introduction of the vehicle the levers
50 B B on opposite sides thereof are connected
at their lower ends with a cross-bar D by rods
or bars d d, and to the middle of the cross-
bar D is attached a rod E, which is provided

with a hook at its opposite end for engage-
ment with a staple e in the flooring forming
the foundation upon which the frame A rests 55
and upon which the vehicle is drawn for the
purpose of loading.

The levers B B terminate at their upper
ends, when they are in an upright or nearly
upright position, a little above the bolsters or 60
body of the vehicle upon which the load is to be
transferred, and upon them are loosely placed
removable cross-pieces F F, on which the lum-
ber or other material to be loaded is properly
piled or arranged for a load, as shown in the 65
right-hand compartment of the apparatus in
Fig. 1. A load being thus arranged and sup-
ported upon the cross-pieces F F, the wagon
or vehicle to be loaded is run under the same,
being guided into the proper position by the 70
guides G G and arrested at the proper point
by the stop G', said guides and stop being at-
tached to the flooring or the foundation upon
which the wagon is placed for loading.

When the wagon or vehicle is placed in po- 75
sition, as just described, and shown in Fig. 2,
the rod E is unhooked and the levers B B al-
lowed to swing back from a vertical toward a
horizontal position, thereby lowering their
upper ends and causing the cross-pieces F F 80
to slide off from the same upon the upper side
beams a a of the frame. The cross-pieces F
being of less thickness than the distance
between the upper sides of the beams a a and
the tops of the bolsters, the load is transferred 85
upon said bolsters, and said cross-pieces are
thus left free, as shown in Fig. 2, and may be
readily withdrawn.

For greater convenience in handling and
loading the lumber or other material, I prefer 90
to construct the apparatus in a number of
sections, like or similar to that described and
shown in the drawings, and to provide an ele-
vated platform or staging H H, upon which
the lumber or other material is received from 95
the cars or other source, assorted, and placed
upon the supports of the loading apparatus.
This arrangement and provision avoids the
necessity of elevating the lumber or other ma-
terial to the loading apparatus and affords a 100
walk for the workmen on a level with the ve-
hicles to be loaded and in convenient prox-
imity to the apparatus, thereby saving time
and labor in assorting, handling, and loading.

The different grades or dimensions of lumber or the various kinds and grades of material may be arranged in the several compartments of the apparatus, each by itself, and the grade, kind, or dimension of the lumber or material indicated by a sign I, placed over or adjacent to the entrance of the compartment in which it is placed, as shown in Fig. 1. The uprights and the cross-piece on which the signs I I are marked serve to brace the frame-work A adjacent to the entrances to the several compartments of the apparatus.

I provide the vehicles, cars, or conveyances employed in connection with my apparatus with bolsters, racks, or platforms, which rise above the tops of the wheels and above the tops of the cross-pieces F F when the latter are lowered upon the beams a a, and for winter use the vehicles may be provided with 20 high runners in place of wheels.

The details of my apparatus may be variously modified, according to the purpose for which it is to be employed, without affecting its mode of operation or departing from the 25 spirit of my invention.

I claim—

1. In an apparatus for loading lumber, &c., the combination, with a suitable frame open at one end to receive the vehicle to be loaded, 30 of levers fulcrumed near their upper ends to the upper beams of said frame to constitute

the portions above said beams, supports for the lumber and the longer portions below the beams, levers for tilting the supports, and bars located beneath the beams connecting 35 the front levers to the rear levers on both sides of the frame, substantially as and for the purposes set forth.

2. In an apparatus for loading lumber, &c., the combination, with a suitable frame open 40 at one end to receive the vehicle to be loaded, of levers fulcrumed near their upper ends to the upper beams of said frame to constitute the portions above said beams, supports for the lumber and the longer portions below 45 the beams, levers for tilting the supports from below, bars located beneath the beams and connecting together the front and rear levers on both sides of the frame, a cross-bar, means connecting the same to the adjacent levers 50 on both sides of the frame, and means for holding the several parts in a locked position until the lumber is to be transferred to the vehicle, substantially as and for the purposes set forth. 55

In testimony that I claim the foregoing as my own I affix my signature in presence of two witnesses.

CHARLES ADAMS GOODYEAR.

Witnesses:

GEO. GRAHAM,

J. M. GRAHAM.
